UNITED STATES PATENT OFFICE.

JOSEPH H. SEBALD, OF EASTON, PENNSYLVANIA.

VALVE.

1,279,920.

Specification of Letters Patent. Patented Sept. 24, 1918.

Application filed October 23, 1917. Serial No. 198,089.

To all whom it may concern:

Be it known that I, JOSEPH H. SEBALD, a citizen of the United States, and a resident of Easton, county of Northampton, State of Pennsylvania, have invented certain new and useful Improvements in Valves, of which the following is a specification.

This invention relates to valves for blowing engines, compressors, pumps and the like, particularly those operating at high speeds.

One of the objects of the invention is to provide a valve, the spring of which will not cause a rotation of the valve as the latter opens and closes, and which, at the same time, will be sufficiently yielding and elastic to permit the rapid operation of the valve.

With this and other objects in view my invention consists of certain novel features of construction, combination and arrangement of parts, as will be more fully described and pointed out in the appended claims.

25 In the drawings, Figure 1 represents a plan and Fig. 2 a sectional elevation of one form of my invention in which the valve and spring are of separate pieces fastened together;

30 Fig. 3 is a plan and Fig. 4 a sectional elevation of one form of my invention in which the valve and spring are integral;

Fig. 5 is a plan and Figs. 6 and 7 sectional elevations of another form of my invention in which two springs are used, Fig. 6 showing the position of the springs when the valve is closed, and Fig. 7, when the valve is open;

Fig. 8 is a plan and Fig. 9 a sectional elevation of another form of my invention in which a plurality of valve rings are provided on the valve; and

Fig. 10 shows in plan another form of spring.

45 The corresponding parts are referred to both in the drawings and in the specification by similar reference characters.

In those forms of valves for quick-acting pumps and the like in which, while the valves have a very short travel, they nevertheless open and close at a high rate of speed, it is essential that they shall be made as light as possible, and that the springs which control them shall be of such a char-

acter as to cause a quick closing. Because of this rapid motion any abnormal distortion of the spring or any abnormal strains thereon are liable to cause a breakage after the valve has been in use for a short time. I have found that one cause of such abnormal strains arises from the fact that in many forms of springs for such valves heretofore used, the arrangement is such that the valve is given a slight rotative movement as it opens and closes. This produces a severe strain on the spring which results in breakage.

To avoid this I have provided a spring of such a character that, when attached to the valve, the latter will have a straight line motion to and from its seat, while at the same time the torsion produced in the spring will be distributed over a considerable length so that no part of the spring is subjected to a severe bending.

75 In connection with my novel construction I am enabled to make the spring and valve of two parts, if I so desire, so that the spring itself may be made of any material suitable for the spring, regardless of the materials or thickness of parts necessary for the valve.

Broadly speaking, my spring comprises a supporting member, usually provided with a central opening by which it may be mounted on the valve seat, this supporting member being provided with a pair of members on each side of and integral with it, the ends of the side members being connected to the ends of the supporting member. Such a spring is connected to the valve preferably at points diametrically opposite the junction between the ends of the supporting arms and the side members.

85 In Fig. 1 I have shown one form of such a spring connected to a valve and arranged for a single annular opening in the valve seat. The spring itself is of sheet metal and comprises the central supporting member 10 and in this form of my invention, a circular member, the two parts of which, 11 and 12, extend on either side of the supporting member 10. The valve ring 13 is provided with a pair of inwardly extending arms 14, 15 connected to the circular members in any suitable manner and preferably by spot welding, as indicated at 16, 16. The opening 17 in the member 10 is provided to slip

over the usual stud extending upwardly from the valve seat. It will be understood that any other means of fastening the central member 10 to the valve seat may be provided. As shown in Fig. 2, when the valve is closed, the spring is flat. As the valve 13 opens, as for instance, by moving upwardly in Fig. 2, the central portion of the member 10 being held fixed, the parts 10, 11 and 12 will be distorted, but by reason of the connections of the members 11 and 12 with each end of the member 10, there will be no rotative movement given to the valve ring, but the latter will move 15 straight upward from its seat.

In the form shown in Figs. 3 and 4, the spring is of the same shape as that shown in Fig. 1, but is formed integral with the valve ring itself. In this form the valve ring 18 and the circular members 19 and 20 and the supporting bar 21 are all stamped from the same sheet metal plate. The action of this valve, when opened, is precisely the same as that of Fig. 1, but in the form shown in Fig. 25 it necessarily follows that it is impossible to make the spring itself of different material from that of the valve ring.

In Figs. 5, 6 and 7 I have shown a form of my invention by which two springs may be used. The valve ring 22 is provided with four inwardly extending members 23, 24, 25 and 26, and a spring is located on either side of the valve. The upper spring has the central supporting member 27, and the two circular side members 28 and 29, the member 28 being spot welded to the arm 23 and the member 29 being spot welded to the member 25. The bottom spring has the supporting member 30 and the circular side members 31, 32, the side member 32 being spot welded to the member 26 and the side member 31 to the member 24.

Fig. 6 shows in cross section the position of these springs when the valve is closed.

Fig. 7 shows the position when the valve is open. It will be understood that proper means are provided by which the centers of the supporting members 27 and 30 are held the proper distance apart, as shown in Fig. 50, and in Fig. 7, the various parts of the spring are shown in the positions approximately which they will occupy when the valve has moved upwardly off its seat.

While in this form of my invention I prefer to provide the four arms 23-26, it will be obvious that instead of setting the supporting arms 27 and 30 at right angles to each other, they may be one directly over the other, in which case the spot welding will occur on the opposite sides of a pair of oppositely disposed members extending inwardly from the valve ring 22, in which event only two of such members will be required.

In Figs. 8 and 9 I have shown a form of

valve in which three rings, 33, 34, 35 are provided for as many circular parts in the valve seat. In this valve the center supporting member 36 is connected to the circular spring members 37 and 38 which, in turn, are preferably spot welded at 39 and 40 to the valve. This form of valve is particularly desirable where the central parts are so small that a sufficient length of spring could not be obtained except by the arrangement indicated in Fig. 8.

In this form of valve if the valve rings have any considerable motion away from the seat, it may be desirable to space the spring vertically away from the valve ring in Fig. 9 so as to prevent the inner ring 35 from striking the supporting member 36, and thus preventing the proper flexing of the spring. Such spacing can be accomplished, of course, by any suitable spacing member between the spring and valve at the point of connection between them.

In Fig. 10 I have shown another form of spring which could be used with many forms of valve, particularly that shown in Fig. 1. While the circular form shown in various illustrative forms of my invention would be preferable because of its symmetry, especially in relation to the usual circular valve, it will be obvious that such a form of spring, as is shown in Fig. 10, will accomplish the same results. In this form the central member 41 is separated from the side members 42 and 43 by shearing to produce the narrow openings 44, 45. The arms 46, 47 enable the side arms to be connected to a circular valve ring, such as shown in Fig. 1.

While I have referred to a valve ring and spring as having separate functions, it will be understood that in such forms as Fig. 3, for instance, the spring itself may also serve as a valve ring, and this same explanation applies to such forms as shown, for instance, in Fig. 1, except that in such event the members 14, 15 would necessarily be given a slight bend so as to engage the top instead of the bottom of the circular side members 11, 12 in order to enable those members to lie in the same plane as the valve ring 13.

The shape of the spring can be varied widely and will necessarily be varied if the form of the valve is varied. But in order to carry out my invention it is required that the side members be connected to each end of the central or supporting member so that, as the springs distort, the motion will be such that there will be no tendency to rotate the valve.

I claim:

1. A sheet metal valve and a sheet metal spring therefor, said spring comprising a narrow supporting member and a pair of oppositely disposed side members integral therewith and extending lengthwise thereof, each of said side members having its ends

connected with the ends of said supporting member and being otherwise unconnected with said supporting member, and said valve being connected to said spring only to each of said side members between its ends.

2. A sheet metal valve and a pair of sheet metal springs therefor, said springs being located on opposite sides of said valve, each of said springs comprising a narrow supporting member and a pair of oppositely disposed side members integral therewith and extending lengthwise thereof, each of said side members having its ends connected with the ends of said supporting member and each

of said side members being connected between its ends to said valve.

3. A sheet metal valve and a sheet metal spring therefor, said spring comprising a circular member and a supporting member extending diametrically of said circular member and integral therewith and connected to said circular member only at its ends, said spring being connected to said valve only at points on said circular member remote from the ends of said supporting member.

JOSEPH H. SEBALD.
